SMOKING PIPE

Joseph A. Smith, New York, N. Y.

Application June 9, 1948, Serial No. 31,909

20 Claims. (Cl. 131—192)

1

This invention relates to smoking pipes with jointed stems.

An object of this invention is to provide a smoking pipe including a bowl, a mouthpiece and a stem in between the bowl and the mouthpiece and knuckle joints connecting the stem to the bowl and the mouthpiece, the stem and mouthpiece being adapted to be folded into positions closely adjacent the bowl when the pipe is not in use, the knuckle joints being leak proof.

Another object of this invention is to provide a smoking pipe including a bowl, a mouthpiece and a stem between the mouthpiece and to the bowl, hollow joints pivotally connecting the stem to the mouthpiece and the bowl, the stem portion being jointed to the bowl by means of joint members, the joints being so constructed as to form interconnecting passages between the mouthpiece, stem and the bowl and allowing the passage of a pipe cleaner therethrough when the stem and mouthpiece portions are in their normal position relative to the bowl, the stem and mouthpiece portions being adapted to be swung about their interconnecting joints into positions adjacent the bowl, the joint members when in such position being adapted to admit the entrance of separate pipe cleaners into the mouthpiece portion and the bowl portion for cleaning the separate portions individually.

A further object of this invention is to provide a smoking pipe which includes a bowl, a mouthpiece and a stem interconnecting the bowl and the mouthpiece, a joint member interconnecting the bowl and one end of the stem and a second joint member interconnecting the mouthpiece and the other end of the stem whereby the stem may be moved to a position adjacent the bowl and the mouthpiece may be moved to a position over the bowl, the bowl including a tubular passage member extending to the first joint member, the mouthpiece including a tubular passage member extending to the second joint member, the stem portion including a tubular passage member aligned with the passage members on the bowl and the mouthpiece and including spring pressed portions at opposite ends thereof which engage opposed end portions of the tubular passages on the bowl and mouthpiece whereby leakage at the joints is prevented when the pipe is in use.

Still another object of this invention is to provide a smoking pipe comprising a bowl having an extension, and a stem portion, a knuckle joint pivotally connecting the stem portion to the extension and including a member removably mounted in said extension.

2

Other objects of this invention will in part be obvious and part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a longitudinal vertical sectional view through a smoking pipe embodying the invention;

Fig. 2 is a top plan view of parts of the horizontal sections of the stem portion and bowl extension showing the joint members;

Fig. 3 is a vertical sectional view through the bowl and stem sections showing the stem section in folded position relative to the bowl;

Fig. 4 is a front elevational view of the pipe in its normal condition with a pipe cleaner inserted therein;

Fig. 5 is a front elevational view thereof, in its folded condition with two pipe cleaners inserted therein;

Fig. 6 is an end view thereof;

Fig. 7 is a top plan view of a portion of the joint member;

Fig. 8 is a side elevational view thereof;

Fig. 9 is an end view thereof;

Fig. 10 is a transverse sectional view of the knuckle portion of the jointed member and illustrating a modification thereof;

Fig. 11 is a side elevational view thereof;

Fig. 12 is an enlarged axial sectional view of a bowl and a removable joint portion, illustrating a modified form of the invention;

Fig. 13 is a plan view of the removable joint portion thereof; and

Fig. 14 is a horizontal sectional view of a knuckle joint embodying the invention and illustrating a modification thereof.

Referring in detail to the drawings, 10 designates a smoking pipe embodying the invention.

15 The same comprises a bowl portion 11, to which is jointedly connected a stem portion 12 from which extends a mouthpiece portion 13, jointedly connected thereto.

The bowl portion 11 comprises the usual substantially cylindrical upstanding wall 15 having a bottom portion 15a. Extending from the bottom portion 15a is a cylindrical extension or boss 16 disposed at right angles to the vertical axis of the bowl. The boss 16 is formed with an axial passage 17 extending into bottom portion

15a. From the passage 17 there extends upwardly a pair of short passages 18, 19 communicating with the interior of the bowl portion 11. The boss 16 is also formed with a counterbore 20 extending from the end 21 thereof, towards the passage 18, but terminating short thereof.

Fitted into the counterbore portion 20 of the boss 16 is a joint member 22 which comprises a cylindrical portion 23 received in the counterbore and provided with externally knurled surfaces 24 to frictionally engage the wall of the counterbore 20. The portion 23 may be formed with an annular groove 25 intermediate its ends. The member 22 may be fixed in bore 20 by means of an adhesive applied to the knurled surface and groove in the member, previous to insertion into the bore. Extending from the portion 23 is an enlarged cylindrical portion 26 having an external diameter equal to the external diameter of boss 16 and including an inner radial surface 27 adapted to abut the surface 21 on the boss. Extending upwardly from the bottom of cylindrical portion 26 is a transverse radially disposed surface 28 parallel to surface 21 and terminating short of the longitudinal axis of the portion. Extending from the upper edge of surface 28 is a transverse part cylindrical surface 29 whose axis is at right angles to the longitudinal axis of the portion 26, and which terminates above the longitudinal axis of the portion. Extending from the upper edge of the cylindrical surface 29 is a planar surface 30 which is inclined rearwardly and upwardly toward the upper surface of portion 26 at an angle of substantially 45°. The portions 23 and 26 are formed with an axial through passage 31 which extends to surface 29 and communicates with passage 17 in boss 16.

The portion 26 is also formed with a pair of similar cut out curved recesses 32 with dovetail cross sections on opposite sides thereof which intersect the surfaces 28, 29 and 30. Each recess 32 comprises a part cylindrical surface 33 having a radius larger than the radius of surface 29. The surface 33 is concentric with cylindrical surface 29. The surface 33 extends inwardly toward passage 31 but terminates short thereof. A surface 34 extends from the inner edge of surface 33 to the outer edge of surface 29, said surface 34 being conically inclined inwardly from the edge of surface 29 to the surface 33, as shown in Fig. 7, forming an arcuate dovetailed recess.

The stem portion 12 comprises a cylindrical member 35 formed with an axial passage 36. Inserted into one end of the passage 36 is a joint member 37, cooperable with joint member 22 in the manner hereinafter described. The joint member 37 comprises a cylindrical portion 38 having an external diameter which permits the member to be fitted into passage 36 of member 35 and adhesively secured therein. The member 37 also includes a cylindrical portion 39 of enlarged diameter equal to the outside diameter of member 35. The portion 39 includes a radial surface 40 adapted to abut the radial surface 28 on joint member 22. The radial surface 40 terminates short of the axis of portion 39 and has extending therefrom a transverse part cylindrical surface 41 having the same radius of curvature as cylindrical surface 29 whereby when surfaces 28, 40 of members 22, 37 are in abutting relation, the surfaces 29, 41 form a continuous part cylindrical surface, as shown in Fig. 1. The portion 39 also is formed with a transverse, planar surface 42 extending from

5

the upper edge of cylindrical surface 41 to the outer surface of portion 39, being inclined upwardly and forwardly, substantially at an angle of 45°.

10 The member 37 is formed with an axial passage 43 extending through portions 38, 39 and coaxial with passage 31 on member 22 and having a diameter larger than the diameter of passage 31 in member 22. The member 37 is also formed with recesses 32 on portion 39, similar to those on member 22. When the members 22, 37 have their surfaces 28, 40 in abutting relation, the surfaces 33, 34 form a continuous curved groove extending from one member to the other. A member 37a which is entirely similar to member 37 is fitted into the opposite end of stem portion 12 and adhesively secured therein. The member 37a has a passage 43 coaxial with passage 43 on member 37.

15 A tubular member 45 is axially disposed within the passage 36 of stem 12 with an external diameter less than the internal diameter of passages 43 and with its end portions projecting into passages 43 of members 37, 37a.

20 The tubular member 45 is positioned within passages 43 of members 37, 37a by means of a pair of similar headed tubular members 46 which are slidably disposed at opposite ends of the passages with their inner ends telescoped into the ends of member 45. The cylindrical head portion 48 of members 46 slidably engages the inner surface of passage 43 and forms an annular shoulder 48a. The head portions 48 include an outer part spherical surface 49. An axial through passage 50 formed in member 46 extends from surface 49 and communicates with the interior of tubular member 45. A coil spring 51 is mounted on member 45, being disposed between the outer surface of the member and the inner surface of passage 43 of members 37, 37a. The ends of the spring 51 engage the shoulders 48a on members 46, urging them outwardly of passages 43 in members 37, 37a for the purpose hereinafter appearing.

25 The members 22, 37 are pivotally jointed together by means of a knuckle 55. The knuckle 55 comprises an intermediate cylindrical portion or cock pin 56 formed with a transverse through opening 57. The outer surface of portion 56 is complementary to the cylindrical surfaces 29, 41 of the members 22, 37. Extending from one side of portion 56 is an enlarged circular head 58. As shown in Fig. 2, the head 58 is disposed so that its axis is at right angles to passage 57 in portion 56. The head 58 comprises an outer planar surface 60, from which extends a cylindrical surface 61. The surface 61 is complementary to surfaces 33 on members 22, 37. Extending from the inner edge of surface 61 to the portion 56 is an undercut conical surface 62 complementary to the surface 34 of members 22, 37. Surfaces 28 and 40 are in planes passing through the axis of the cock pin 56.

30 A head 58a similar to head 58 is formed with an axial opening 63 which is adapted to receive the end of portion 56 opposite head 58, being force fitted thereon. The head 58a is also formed with an under cut conical surface 62 complementary to the surface 34 of members 22, 37. The portion 56 of the knuckle 55 is formed with a concave socket or recess 66 at one end of opening 57. The recess 66 is complementary to the surface 49 of headed member 46 and is adapted to receive the same when the member 46 is properly aligned with the knuckle 55.

The knuckle 55 interconnects members 22, 37, as shown in Figs. 1 and 2, being assembled with the members by positioning the knuckle to engage complementary portions of the members and forcing head 58a on portion 56. A tubular member 67 is mounted in passage 31 of member 22 and projects into opening 57 in the knuckle, with its end formed to conform to the concavity of recess 66. The member 67 fixes the knuckle 55 against movement relative to member 22. The complementary dovetailed surfaces 62, 34 on knuckle 55 and members 22, 37, permit pivotal movement of the member 37 and attached stem portion 12 relative to member 22 and attached bowl 11 yet sealing the coaxial members 46, 67 against leakage at the joint, when the members 22, 37 are in alignment. With surfaces 23, 40 in abutting relation, surfaces 30, 42 will be at an angle of 90° relative to each other. The spring 51 presses headed member 46 against portion 56 of the knuckle to insure against leakage, the head portion 49 being received in recess 66.

When stem portion 12 is swung up into the position shown in Fig. 3 with surfaces 30, 42 abutting, the headed member 46 is moved rearwardly within tubular member 45 against spring 51 and rides over the cylindrical surface of portion 56 of the knuckle 55. In this position, the tubular member 67 is accessible for the admission of a pipe cleaner 70, as shown in Fig. 5.

The mouthpiece portion 13 comprises a joint member 22a which is similar to member 22 except as hereinafter described. The member 22a includes a cylindrical portion 27a which is formed with an axial passage 71 extending forwardly from the part cylindrical surface 29. Co-axial with passage 71 and extending to surface 72 of member 22a is a counterbore 73. A mouthpiece 74 of hard rubber or other suitable material is fitted into counterbore 73. A tubular member 67a somewhat similar to member 67 but shorter than member 67, is fitted into passage 71 so as to communicate with the axial passage 75 in mouthpiece 74. The member 67a fixes a second knuckle member 55 entirely similar to that previously described in the manner previously described. It follows that the second knuckle member 55, which interconnects the member 22a on mouthpiece portion 13 with member 37a on stem portion 12, permits the mouthpiece portion 13 to be moved relative to the stem portion 12, as shown in Fig. 5. This allows another pipe cleaner 70 to be inserted into the tubular member 67a and to be pushed through the passage 74 in mouthpiece 75 to clean the same. It follows that the mouthpiece portion and the bowl portions may be separately cleaned. Additionally, when the mouthpiece and stem portions are in their normal aligned position and aligned relative to the bowl portion, the successive portions may be cleaned by a single cleaner 70 inserted in the mouthpiece and pushed through the successive passages. As shown in Fig. 1, the openings in knuckles 55 will permit free passage of the cleaner. It is also apparent that the arrangement of spring pressed members 46 relative to the recesses or sockets 66 on the knuckles 55 is effective to maintain the aligned relationship of mouthpiece, stem portion and extension.

The spring pressed members 46 are also effective to frictionally engage surface portions of the knuckles 55 when the stem portion 12 and mouthpiece 13 are in their folded position relative to

the bowl 11 thereby keeping the folded members in folded position.

The pipe 10, which is in its extended form, as shown in Fig. 4, may be readily folded when not in use, as shown in Fig. 5. The stem portion 12 is folded about knuckle 55 until the planar edges 30, 42 on members 22, 37 thereof abut. This brings the stem portion 12 into a position parallel to the axis of bowl 11. The mouthpiece portion is then swung about its knuckle to a position overlying the top of bowl 11. The inclined planar portions 30, 42 of the members 22a, 37a determine the position of the mouthpiece portion 13 relative to the top of the bowl.

In Figs. 10 and 11 is shown a knuckle member 80 similar to member 55 except that the intermediate portion 81 interconnecting heads 58, 58a, is part spherical instead of cylindrical. The joint members 82 are similar to joint members 22, 37 except that they are formed with a transverse part spherical surfaces 83 to properly seat the portions 81 of the knuckle 80.

In Figs. 12 and 13 is shown a form 10a of the invention and illustrating a modification thereof. The same comprises a bowl portion 11a having a cylindrical extension or boss 85 extending from the bottom thereof. Boss 85 is formed with an axial passage 86 which is interconnected by passage 18 to the interior of bowl 11a. The outer edge 87 of boss 85 is formed with an annular shallow recess 88. The boss 85 is also formed with an annular groove 89 extending from recess 88 inwardly towards passage 18, but terminating short thereof. The groove 89 has a tapering cross section as shown in Fig. 12.

A thimble 90 is fitted into groove 89, being adhesively or otherwise secured therein. The thimble 90 comprises an annular flange 91, which fits into recess 88. Extending from flange 91 is a cylindrical wall 92 which contacts the outer surface of groove 89. A conical wall 93 extends outwardly from the inner end of wall 92 and contacts the inner surface of groove 89. The outer edge of wall 93 is in the plane of flange 91 of wedge shaped cross section. The walls 92, 93 form an annular groove 94.

A joint member 22b similar in all details to member 22, except as hereinafter described, is removably fitted into thimble 90. The member 22b comprises a cylindrical portion 100 which is formed with an axial through passage 31 which is adapted to communicate with passage 86 in boss 85. Extending rearwardly from portion 100, is an annular flange 101 of transverse wedge shaped cross section. The flange 101 forms a shoulder 102 which is disposed in contact with flange 91 of thimble 90, the flange 101 being received in groove 94. The flange 101 is formed with opposed longitudinal slots 103, which permits the flange to be constricted when wedged into groove 94. Also extending from portion 100 is an annular flange 104 which is adapted to be disposed in contact with the surface of passage 86 in boss 85.

In this form of the invention, the joint member 22b together with attached stem portion 12 and mouthpiece 13, may be removed from the bowl 11a, thereby facilitating the cleaning of passage 86 in the bowl.

In Fig. 14 is shown a knuckle joint 110 which embodies the invention and illustrates a modification thereof. The same comprises a knuckle 111 which interconnects the joint members 112, 113. The knuckle 111 comprises a member 114 having a hollow stem or intermediate portion

115 with a circular head 116 at one end thereof. The head 116 is formed with an annular undercut 117 of rectangular transverse cross section on the inner side thereof forming a flange 118. The knuckle 111 further comprises a member 119 having a stem or intermediate portion 120 receivable in hollow stem portion 115 of piece 114. The stem 120 is provided at one end thereof with a circular head 116a similar to head 116. The head 116a is formed with an annular undercut 117a similar to undercut 117 and forms a flange 118a. The stem portion 120 is formed with a transverse through passage 121 and stem portion 115 is formed with aligned openings 122. The joint members 112, 113 are entirely similar to joint members 22, 37, respectively, except that they are formed with annular recesses 125 on opposite sides thereof which are complementary to the flanges 118, 118a on the heads 116, 116a.

The knuckle joint 110 is formed by assembling the joint members 112, 113 with knuckle members 114 and then force fitting the stem portion 120 of knuckle member 119 into the hollow of knuckle piece 114. The openings 122 in stem portion 115 are adapted to register with the passage 121 in stem portion 120 when the knuckle is in its final assembled form, as shown in Fig. 14. The tubular member 67 fixes the knuckle 111 to the member 112. The stem portion 115 is formed with a recess 126 at one of the openings 122 to receive the portion 49 of spring pressed member 46.

The undercuts 117, 117a on the knuckle 111 are adapted to substantially eliminate play at the joints. The openings 122 and passage 121 in the knuckles allow the entry of pipe cleaners 70, in the manner previously described.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. A smoking pipe comprising a bowl having an extension, a stem portion, joint members affixed to the ends of said extension and said stem portion and a knuckle joint interconnecting said joint members, said stem portion, knuckle joint, joint members and extension being formed with straight, coaxially, aligned through passages, said knuckle joint comprising a member having an intermediate portion extending transversely of the stem portion, and circular heads at opposite ends of said intermediate portion, said heads being of dovetail cross-section, one of said heads being annular and said joint members having grooves to receive said heads and portions contacting said intermediate portion.

2. In a smoking pipe comprising a bowl having an extension and stem portion, a joint between said extension and stem portion comprising a pair of joint members and a knuckle between said members, said members being formed with through passages, said knuckle comprising an intermediate portion formed with a through passage adapted to be aligned with the through passages in said joint members, and circular heads at opposite ends of said inter-

mediate portion, said heads being formed with inner conical surfaces, said joint members having surfaces contacting one another when said stem portion and extension are in alignment and said joint members having surfaces disposed at 90° to one another and at 225° to the first mentioned surfaces when said first mentioned surfaces contact one another, and said second mentioned surfaces being adapted to contact one another when said stem portion is swung to a position at right angles to said extension, said joint members having curved grooves complementary to and adapted to receive parts of said circular heads and means to fix said intermediate portion to a joint member.

3. In a smoking pipe comprising a bowl having an extension and stem portion, a joint between said extension and stem portion comprising a pair of joint members and a knuckle between said members, said members being formed with through passages, said knuckle comprising an intermediate portion formed with a straight through passage adapted to be aligned with the through passages in said joint members and coaxially therewith, and circular heads at opposite ends of said intermediate portion, said heads being formed with inner conical surfaces, said joint members having surfaces contacting one another when said stem portion and extension are in alignment and said joint members having surfaces disposed at 90° to one another and at 225° to the first mentioned surfaces when said first mentioned surfaces contact one another, and said second mentioned surfaces being adapted to contact one another when said stem portion is swung to a position at right angles to said extension, said joint members having curved grooves complementary to and adapted to receive parts of said circular heads and means to fix said intermediate portion to a joint member, said means including a tube extending into the through passage in the intermediate portion and also into a joint member.

4. In a smoking pipe comprising a bowl having an extension and stem portion, a joint between said extension and stem portion comprising a pair of joint members and a knuckle between said members, said members being formed with through passages, said knuckle comprising an intermediate portion formed with a through passage adapted to be aligned with the through passages in said joint members, and circular heads at opposite ends of said intermediate portion, said heads being formed with inner conical surfaces, said joint members having surfaces contacting one another when said stem portion and extension are in alignment and said joint members having surfaces disposed at 90° to one another and at 225° to the first mentioned surfaces when said first mentioned surfaces contact one another, and said second mentioned surfaces being adapted to contact one another when said stem portion is swung to a position at right angles to said extension, said joint members having curved grooves complementary to and adapted to receive parts of said circular heads and means to fix said intermediate portion to a joint member, said means including a tube extending into the through passage in the intermediate portion and also into a joint member, and a spring pressed tubular member within the joint member in said stem portion adapted to contact said intermediate portion, the passage in said spring pressed tubular member communicating with the pas-

sage in the intermediate portion when said stem portion is in alignment with said extension.

5. A smoking pipe comprising a bowl formed with an extension, a mouthpiece and a stem portion between said extension and mouthpiece, and knuckle joints interconnecting said stem portion with said extension and mouthpiece respectively, each knuckle joint comprising a pair of joint members and a knuckle between said joint members, each knuckle comprising an intermediate portion formed with a through passage, and circular heads at the ends of each intermediate portion, the said heads having conical under cut surfaces at their inner sides and said joint members having portions engaging said under cut surfaces and portions engaging said intermediate portion, said extension being formed with a through passage and said stem portion and mouthpiece being formed with through passages, said through passages being in straight coaxial alignment with one another and forming a smoke passageway through which a pipe cleaner may be inserted without bending.

6. A smoking pipe comprising a bowl formed with an extension, a mouthpiece and a stem portion between said extension and mouthpiece, and knuckle joints interconnecting said stem portion with said extension and mouthpiece respectively, each knuckle joint comprising a pair of joint members and a knuckle between said joint members, each knuckle comprising an intermediate portion formed with a through passage, and circular heads at the ends of each intermediate portion, the said heads having conical under cut surfaces at their inner sides and said joint members having portions engaging said under cut surfaces and portions engaging said intermediate portion, said extension being formed with a through passage and said stem portion and mouthpiece being formed with through passages, said through passages being in straight coaxial alignment with one another and forming a smoke passageway through which a pipe cleaner may be inserted without bending, and means for attaching one knuckle with its joint members to said extension and said stem portion and the other knuckle with its joint members to said mouthpiece and said stem portion.

7. A smoking pipe comprising a bowl formed with an extension, a mouthpiece and a stem portion between said extension and mouthpiece, and knuckle joints interconnecting said stem portion with said extension and mouthpiece respectively, each knuckle joint comprising a pair of joint members and a knuckle between said joint members, each knuckle comprising an intermediate portion formed with a through passage, and circular heads at the ends of each intermediate portion, the said heads having conical under cut surfaces at their inner sides and said joint members having portions engaging said under cut surfaces and portions engaging said intermediate portion, said extension being formed with a through passage and said stem portion and mouthpiece being formed with through passages, and means for attaching one knuckle with its joint members to said extension and said stem portion and the other knuckle with its joint members to said mouthpiece and said stem portion, and spring pressed tubes in the through portion of said stem portion pressing against said intermediate portions, and communicating with the passages in said intermediate portion when said extension, stem portion and mouthpiece are in alignment.

8. A smoking pipe comprising a bowl portion including an extension formed with a passage, a stem portion formed with a passage, a joint pivotally connecting the stem portion to the extension, a mouthpiece portion formed with a passage, a joint pivotally connecting the mouthpiece portion to the stem portion, one of said joints comprising a knuckle formed with an opening connecting the passages in said bowl portion and stem portion, the other of said joints comprising a knuckle formed with an opening connecting the passages in said mouthpiece portion and stem portion, a hollow member slidably mounted within each end of the passage of said stem portion, each of said slidably members contacting a knuckle, the hollow portion of each of said hollow members registering with the opening in the contacting knuckle and resilient means for maintaining said hollow members in engagement with said knuckles whereby to prevent leakage at said joints.

9. A smoking pipe comprising a bowl portion including an extension formed with a passage, a stem portion formed with a passage, a joint pivotally connecting the stem portion to the extension, a mouthpiece portion formed with a passage, a joint pivotally connecting the mouthpiece portion to the stem portion, one of said joints comprising a knuckle formed with an opening connecting the passages in said bowl portion and stem portion, the other of said joints comprising a knuckle formed with an opening connecting the passages in said mouthpiece portion and stem portion, a hollow member slidably mounted within each end of the passage of said stem portion, each of said slidably members contacting a knuckle, the hollow portion of each of said hollow members registering with the opening in the contacting knuckle, and resilient means for maintaining said hollow members in engagement with said knuckles whereby to prevent leakage at said joints, each of said knuckles being formed with a recess at one end of the opening in said knuckle, each of said slidably members being formed with a surface complementary to the recess in the adjacent knuckle and received therein when the stem and mouthpiece portions are aligned with said bowl extension.

10. A smoking pipe comprising a bowl, a mouthpiece, a stem portion, knuckle joints between the stem portion and the mouthpiece and the stem portion and the bowl whereby the stem portion may be swung upwardly to parallel the bowl and the mouthpiece may be swung downwardly over the upper end of the bowl, the mouthpiece, stem portion, knuckle joints and the bowl each being formed with a through passage, said stem portion having means to uncover the passages in the knuckle joint connecting said stem portion to the bowl when said stem portion is swung upwardly to a position parallel to the bowl, and said mouthpiece having means to uncover the passage in the mouthpiece when swinging said mouthpiece from a position in alignment with the stem portion to a position at right angles to the stem portion, and spring pressed means comprising slidably tubular members in said stem portion to contact said knuckle joints for sealing the passages against leakage in said knuckle joints.

11. In a smoking pipe, a bowl extension and a stem portion, a joint between said extension and stem portion comprising a pair of joint members and a knuckle between said members, said members being formed with through passages, said 75 knuckle comprising an intermediate portion fixed

11

to a joint member and formed with a through passage adapted to be aligned with the through passages in said joint members, and circular heads at opposite ends of said intermediate portion, said heads being formed with inner conical surfaces, said joint members having surfaces contacting one another when said stem portion and extension are in alignment and said joint members having surfaces disposed at 90° to one another and at 225° to the first mentioned surfaces when said first mentioned surfaces contact one another, and said second mentioned surfaces being adapted to contact one another when said stem portion is swung to a position at right angles to said extension, and said joint members having curved grooves complementary to and adapted to receive said conical surfaces of said circular heads.

12. In a smoking pipe, a bowl extension and a stem portion, a joint between the extension and stem portion comprising a member formed with a through passage which is fixed to the extension and formed with dovetail recesses, a second member formed with a through passage, fixed to the stem portion and formed with dovetail recesses similar to those on said first mentioned member and a knuckle engaging said members and permitting pivotal movement of said stem portion relative to said bowl, said knuckle being fixed to the member on the bowl and being formed with a through passage aligned with the passages in said members and being further formed with portions disposed in the dovetail recesses in said members.

13. In a smoking pipe, a joint comprising a pair of aligned members pivotally interconnected by a knuckle, each of said members being formed with a passage adapted to be aligned with each other when said members are aligned with each other, said knuckle including an intermediate portion formed with a passage interconnecting the passages in said members when said members are aligned, and a tubular member disposed in the passage in one of said members and the passage in the knuckle to fix said knuckle relative to said one member, and interengageable means on said members and said knuckle to retain said knuckle against transverse movement relative to said members, said members forming a right angle and having means exposing passages in the intermediate portion, when the pipe is in a folded position.

14. A smoking pipe comprising an extension formed with a passage, a stem portion formed with a passage, means pivotally interconnecting said extension and stem portion, said interconnecting means being formed with passages interconnecting the passages in said extension and said stem portion when said extension is aligned with said stem portion, a mouthpiece portion formed with a passage, means pivotally interconnecting said mouthpiece portion and said stem portion, said last mentioned interconnecting means being formed with passages interconnecting the passages in said mouthpiece and stem portion when said mouthpiece portion is aligned with said stem portion, a tubular member in the passage of said stem portion, a tubular member in the passage of said interconnecting means on said extension, in registering relation to the tubular member in the stem portion when said stem portion is aligned with said extension, and a tubular member in the passage of said interconnecting means on the mouthpiece portion in registering relation to the tubular member in the

12

stem portion when said mouthpiece portion is aligned with said stem portion.

15. In a smoking pipe comprising a bowl extension and a stem portion, a joint between the bowl extension and stem portion comprising a member formed with a through passage, and mounted on the bowl extension and formed with arcuate recesses in opposite sides thereof, a second member formed with a through passage, fixed to the stem portion and formed with arcuate recesses in opposite sides thereof, and a knuckle fixed to the member on said bowl extension, and engaging the other member for permitting pivotal movement of said stem portion relative to said bowl extension, said knuckle being formed with a passage adapted to be aligned with the passages in said members and being formed with circular flange portions disposed in the recesses in said members.

16. A smoking pipe comprising a bowl extension formed with a passage, a first joint member on the bowl extension, said first joint member being formed with a passage communicating with the passage in said bowl extension, a cock pin fixed on said first joint member and formed with a through passage traversing the axis of said cock pin and in communication with the passage in said first joint member, a second joint member pivotally connected to said cock pin, a stem portion having one end attached to said second joint member, a third joint member at the other end of said stem portion, said stem portion and its attached joint members being formed with passages therethrough, a mouth piece portion, a fourth joint member thereon provided with a fixed cock pin pivotally connected to said third joint member, said last cock pin's mouth piece and fourth joint member being formed with through passages traversing the axis of said last mentioned cock pin, all of said passages forming a straight, continuous, through passage when said stem portion and mouth piece portion are in alignment with said bowl extension so that a pipe cleaner can be passed therethrough, said mouth piece portion and its fourth joint member being swingable upwardly through an angle of ninety degrees to the stem portion, and said stem portion and its second and third joint members being swingable together with the upswung mouth piece upwardly through an angle of ninety degrees to the first joint member, the front end of said through passage in said first cock pin being uncovered in the said upswung position of said stem portion to allow a pipe cleaner to be passed therethrough, and the rear end of the through passage in said second cock pin being uncovered in said upswung position to allow passage of a pipe cleaner therethrough and through the mouth piece portion.

17. In a smoking pipe, a first stem portion formed with an axial passage therethrough, a second stem portion formed with an axial passage therethrough, a pair of pivotally interconnected joint members, swingable from one extreme position of ninety degrees with respect to each other to a second fixed extreme position of one hundred and eighty degrees with respect to each other, and each formed with an axial passage, one of said joint members being attached to one end of said first stem portion, and a cock pin formed with a transverse through passage, fixed on said last mentioned joint member, the other joint member being attached to one end of said second stem portion, the passage in the first stem portion, the passage in the joint mem-

ber attached thereto, and the passage in said cock pin being in straight, coaxial alignment and in communication with each other and forming a continuous duct and said passage in said cock pin being uncovered by the second joint member when said joint members are ninety degrees with respect to each other, whereby a pipe cleaner may be inserted through the passages in said cock pin, said first joint member and first stem portion for cleaning.

18. The combination of claim 17 in combination with a mouth piece portion formed with an axial passage therethrough, a second pair of pivotally interconnected members swingable from one fixed extreme position of ninety degrees with respect to each other, to a second fixed extreme position of one hundred and eighty degrees with respect to each other, and formed with an axial passage in each of said members of said second pair, one of said members of said second pair being attached to the other end of said second stem portion, the other member of said second pair being attached to said mouth piece portion, a second cock pin formed with a transverse through passage being fixed on said last mentioned member of said second pair, the passage in the mouth piece portion, the passage in the member attached thereto, and the passage in said second cock pin being in straight, coaxial alignment and in communication with each other and forming a continuous duct, whereby a pipe cleaner may be inserted therethrough for cleaning purposes when said members of said second pair are ninety degrees with respect to each other.

19. The combination of claim 18, the passages

5

in said second stem portion and joint members attached thereto being in straight coaxial alignment, and in communication with each other, and forming a continuous duct closed at both ends

5 when said members in each pair are ninety degrees with respect to each other.

10 The combination of claim 18, the passages in said second stem portion and joint members attached thereto being in straight coaxial alignment, and in communication with each other, and forming a continuous duct closed at both ends when said members in each pair are ninety degrees with respect to each other, all of said ducts being in straight coaxial alignment and forming a continuous smoke passage when said members in each pair are one hundred and eighty degrees with respect to each other.

15 JOSEPH A. SMITH.
